[57] CLAIM

The ornamental design for a telephone handset housing, as shown and described.

DESCRIPTION

FIG. 1 is a top plan view showing the telephone handset housing of our new ornamental design;

FIG. 2 is a left side elevation thereof, the right side elevation thereof being substantially a mirror image of the left side;

FIG. 3 is a bottom view thereof;

FIG. 4 is a front elevation thereof;

FIG. 5 is a rear elevation thereof;

FIG. 6 is a sectional view, showing the contour of the outer surface of the housing, taken along line 6—6 of FIG. 1;

FIG. 7 is a sectional view, showing the contour of the outer surface of the housing, taken along line 7—7 of FIG. 6; and,

FIG. 8 is a sectional view, showing the contour of the outer surface of the housing, taken along line 8—8 of FIG. 6.
